UNITED STATES PATENT OFFICE.

JAMES M. STOCKER, OF ATLANTA, GEORGIA.

HEATING-TANK.

1,394,692.

Specification of Letters Patent. Patented Oct. 25, 1921.

Application filed August 2, 1919. Serial No. 314,990.

To all whom it may concern:

Be it known that I, JAMES M. STOCKER, a citizen of the United States, residing at Atlanta, in the county of Fulton and State 5 of Georgia, have invented certain new and useful Improvements in Heating-Tanks; and I do hereby declare the following to be a full, clear, and exact description of the invention, such as will enable others skilled 10 in the art to which it appertains to make and use the same.

This invention relates to heating tanks and particularly to steam heating tanks and tanks for the heating of asphalt or other 15 road binders such as are sprayed or poured on a roadway in the penetration process of building roads or for surface treatment of roads, but is not limited thereto.

An object of this invention is to provide 20 a means of obtaining the necessary heat by steam for the liquefaction of current road binders to enable them to be sprayed or poured upon the roadway in a satisfactory manner.

25 A further object of this invention is to provide for the great relative changes in specific gravity of the heated and non-heated portions of the binder which occasions the heated portion of the binder always being 30 at the top under current methods of heating with the colder portion always at the bottom.

35 A further object of this invention is to provide against the precipitation of the newly supplied binder into the heater from immediately carrying it to the drain port of the heater.

40 A further object of this invention is to provide a heated path for the binder being fed into the tank and to equalize the heating of the newly fed binder with that of the binder already in the tank.

45 A further object of this invention is to provide a means for varying the relative heat of the different strata throughout the tank.

50 A further object of this invention is to provide means for providing a relatively greater heat at the bottom of the heating tank than at the top.

55 A further object of this invention is to provide a means of heating by steam the new binders which have such a content of asphalt or bitumen as to make the former methods of heating by steam insufficient to produce the high temperature necessary to

make them liquid enough to be sprayed or poured upon the roadway in a satisfactory manner, and which if heated in kettles with fires is often heated too hot in places which results in the coking of the carbon contained 60 therein and destroying the ductility and cementing qualities of the binder, and which has not been accomplished in a satisfactory, rapid and economical manner.

With these and other objects in view the 65 invention consists of the construction, combination, and in detail and arrangement of parts as hereinafter more fully described and claimed.

In the drawing,

70 Figure 1 is a vertical longitudinal section of my tank with coil 4^a shown only in part.

Fig. 2 is a section of my tank at 2—2 Fig. 3, with coils 4 and 4' shown only in part.

75 Fig. 3 is an end view partly broken away.

The binder is supplied at port 1 and taken 80 from the tank at port 2. This is distinguished from the current designs as will hereafter be more fully understood, the current design having the supply port and the drain port substantially with the supply port directly over the drain port. 3 and 3' are steam inlets and 3^a and 3^b are auxiliary steam inlets. Steam inlets 3 and 3' are joined by pipe 6. Inlets 3^a and 3^b are 85 joined by pipe 7. Inlets 3 and 3' lead respectively to coils 4 and 4'. The respective outlets for coils 4 and 4' are at 5 and 5'. Inlets 3^a and 3^b, respectively, lead to coils 4^a and 4^b. Coils 4^a and 4^b, respectively, have 90 outlets 5^a and 5^b. Suitable valves are provided to regulate and vary the supply and discharge of these pipes. I thus have four sets of coils, being 4, 4', 4^a and 4^b. These coils are substantially below the medial line 95 of the tank and are substantially alike on opposed sides, that is to say, coil 4 is substantially the same as coil 4' and coil 4^a is substantially the same as 4^b. Coils 4 and 4' being connected by pipe 6 can be made a 100 single unit coil; likewise coils 4^a and 4^b being connected by pipe 7 can be made a single unit coil.

The tank is constructed of metal in a circular form having heads at each end as is 105 usual in tanks of this character. Steam inlets and steam outlets are at opposed ends of this tank. The steam inlet for coils 4 and 4' being substantially at half the height of the tank and the outlet for 4 and for 110

4' are slightly above the lower portion of the said tank. The inlet for coils 4^a and 4^b are just below the bottom pipe of the coils 4 and 4' respectively, and the outlet for coils 4^a and 4^b are in or near the bottom of the tank. In former practice it has been customary to divide the heating coils into two sections, each section entering the tank at a point along its outer edge on either side and at a point near the center of elevation. The steam circulating through the coils downward and discharging at the bottom of the tank or through the end near the bottom. This has been done so the condensed water will have the easiest path of exit. In all coils of this type it is self evident that the steam in passing through the pipes will be discharged at a lower temperature than that at which it enters the coil and having a heating value at the bottom of the tank lower than at the top. In asphalt and other bituminous compounds the specific gravity decreases very rapidly as the temperature increases and the hot portion rises to the top of the tank where the temperature is still further increased by the relative hotter steam in the inlet part of the coil while the colder portion settles to the bottom of the tank where the steam in the coils is of lower temperature. The result is that under some conditions the contents of the upper portion of the tank may be hot enough and the lower portion is too cold. As it is commercially necessary to take out the road binder from the bottom of the tank, the colder portion will be drawn off. To overcome this I have arranged the coils in four sections two of which are along the inner sides of the tank as shown at 4 and 4' and the other two are placed along the bottom of the tank having independent inlet means and independent discharge means. By this arrangement of the heating coils it is evident that as the cold portion of the contents of the tank settles to the bottom that it will come in contact with the coils at the bottom, which contain live steam at a high temperature. Each coil is provided with separate valves to control the inlet of the steam and to regulate the discharge of the condensed water and steam which has lost part of its heat by radiation. When two or more coils of this kind are connected up with a common inlet or outlet they will not discharge the condensed water equally on account of the pressure at the inlet of all the coils being equal and the pressure at the outlet of the coils being equal, the difference in friction against the walls of the various coils will cause the water of condensation to accumulate in the coil having the greatest resistance. This will be true even if the various coils are of equal length on account of the difference in the interior surfaces of the pipe of which they are com-

posed. The steam circulates through the coils downward and discharges at the bottom of the tank or through the end near the bottom in current coils. It substantially follows the same course in these coils. This downward course is provided so that the condensed water will have the easiest path of exit. In all coils of this type it is self evident that the steam in passing through the coils will be discharged at a lower temperature than when it enters the coil and has a lower heat value at the bottom of the tank than at the top. The coils 4^a and 4^b I prefer to make of lesser length than coils 4 and 4' and they will therefore if desired be hotter than 4 and 4' but even if not hotter they would naturally, due to the elements above referred to, be relatively hotter than if they were joined as a continuous part of coils 4 and 4' as is the usual practice. By this means it is apparent that I can have the greatest heat at the bottom of the heating chamber and since the colder portions of the binder would, due to its relative specific gravity when heated, be at bottom, I can thereby equalize the heat of this binder and keep it at substantially the same viscosity, and can further heat the binder to a greater temperature than could be had with the old system of coils. This heating to a greater temperature it is apparent will be accomplished by overcoming the radiation from the binder itself which would in the old system tend to normally keep the topmost portion cool and further by the shorter coils 4^a and 4^b being hotter than in the old system and producing a greater heat from below which is radiated upward, raising rather than lowering the temperature of the upper strata. Not only do I accomplish a greater heat but it is also apparent that I am thus enabled to draw out from the bottom the hottest portion of the binder whereas heretofore it was necessary to draw out the colder portion and by reason of this even at equal temperatures I am enabled to utilize binders requiring a higher temperature for liquefaction. I am further enabled to greatly economize on fuel.

These advantages accrue from the operation of the heating coil but my arrangement is a much further advantage. In the system in vogue in applying the substance to be heated in the heater directly above the outlet port precipitation causes it to go directly to the outlet port and therefore the colder binder is drawn at the outlet port. In this new arrangement the supply to be heated precipitates upon hot coils 4^a and 4^b when it is admitted through port 1 and before it reaches the outlet has to travel all the way down the length of the heater. Since normally coils 4^a and 4^b are the hottest coils and since this is the colder substance an equalized temperature is to be had.

Thus I have at the bottom a liquid of as great, and if desired, even greater temperature and relative viscosity than at the top, whereas, in the older system there is a collection of colder portions of the contents of the tank at the bottom where the steam in the coils is not hot enough to heat it. I thus automatically equalize the heat of the old and the new binder in the chamber.

10 The method of operation is as follows:

The tank is located at a point adjacent to a railroad. The road binder is shipped in tank cars. These cars are provided with heating coils sufficient to raise the temperature of the road binder sufficiently to allow the cars to be unloaded. The road binders are pumped from these tanks into the heating tank. The heating tank has sufficient capacity to hold enough for an ordinary 20 day's work. The heating tank being provided with sufficient coils filled with steam at a high temperature, the semifluid road binder is soon heated to high temperature. A part of the contents of the heating tank 25 is pumped into a tank mounted on a wagon or motor truck and carried to the road where it is to be used. A portion of the road binder equal to that removed is then pumped from the tank car into the heating tank 30 through the filling opening 1. As road binder is pumped in slowly a portion of it will mix with the hot content of the heating tank and the remainder will settle to the bottom directly under the filling opening 1 35 where it will come into contact with the coils 4^a and 4^b as described, which will rapidly heat it as it slowly spreads out over the bottom of the tank. By the time it has reached the discharge outlet 2, the heat will be sufficiently high to allow it to be sprayed on the roadway. The heating tank can be mounted 40 on skids or on wheels as desired to make it portable. It can also be covered by a non-

conductor of heat to prevent loss by radiation.

45

I claim:

1. In combination, a tank, a plurality of steam coils in said tank extending longitudinally and arranged adjacent the sides and bottom thereof, each coil having independent means for controlling the supply of steam at one end and independent means for controlling the exhaust of condensed water at the other end.

15 2. In combination, a tank, a plurality of steam coils in said tank extending longitudinally and arranged adjacent the sides and bottom thereof, each coil having independent means for controlling the supply of steam at one end and independent means for controlling the exhaust of steam at the other end, the lower coils being constructed to offer less resistance to the steam than the upper coils.

20 3. In combination, a tank, a plurality of steam coils in said tank extending longitudinally and arranged adjacent the sides and bottom thereof, each coil having independent means for controlling the supply of steam at one end and for controlling the exhaust of condensed water at the other end, the bottom coils containing less pipes than the upper coils.

25 4. In combination, a tank for heating bituminous binders, steam coils in said tank extending longitudinally, laterally opposed sets of said coils connected by a pipe, superposed sets of said coils receiving steam independently, steam inlets at the top of each independent set of coils, a drain cock at the 30 bottom of each independent set of coils, and means for drawing the contents of said tank at an end opposed to the end for filling said tank.

35 In testimony whereof I affix my signature. 85
JAMES M. STOCKER.
